MONEY PACKAGE

Application filed November 9, 1926. Serial No. 147,242.

This invention pertains to packaging money. The principal object is to provide a sealed package of such design that the money therein may be counted before the package is 5 broken open.

Although the invention is of great value in many lines, its value is probably most apparent in connection with the paying of workmen, and the invention is herein illustrated and described as adapted for such use.

The usual method of paying workmen is to place each man's pay in an envelope, with his name on the outside. Sometimes the outside of the envelope also carries figures representing the amount of money the package is supposed to contain and sometimes it even carries a statement of account to show how the amount is arrived at.

In order to count his pay the workman 20 tears open the envelope and withdraws the money. If he thinks there is an error in the amount he takes the matter up with the paymaster, who is often suspicious that the workman has secreted some of the money 25 taken from the package and is therefore inclined to be slow in making adjustments. The fact that the envelope bears on its outside a statement of amount or account, or both, does not prevent disputes because the 30 workman is inclined to think that even if the figures on the envelope are wrong the amount of money may be right, and opens the envelope anyhow.

The present invention prevents all misunderstandings and disputes, due to above conditions, because it permits the counting of the contents of the envelope before breaking it open. It also permits the display of the man's account, as well as the money, before 40 the package is opened.

In short, if there is any dispute as to amount or account, the present invention permits its adjustment before the package is broken, as readily as the former practice permitted such adjustments after the envelope was opened.

Further and other objects and advantages will be hereinafter set forth in the accompanying specification and claims, and shown 50 in the drawings, which by way of illustra-

tion show what is now considered to be the preferred embodiment of the invention.

Fig. 1 shows a money package ready to hand to the workman.

Fig. 2 is a cross section on line 2—2 of 55 Fig. 1.

Fig. 3 shows a portion of a time sheet of a number of workmen as prepared by the timekeeper.

Fig. 4 shows the account of an individual 60 workman, as cut from the sheet in Fig. 3.

Fig. 5 is a cross section on line 5—5 of Fig. 2.

Fig. 6 is a cross section on line 6—6 of 65 Fig. 2.

Fig. 7 shows the device used by the operator for placing the money and statement in the envelope. The device is shown in position in an unsealed envelope.

Fig. 8 shows the inserting device with 70 money and statement arranged thereon, before closing the device.

Fig. 9 is a detail showing the lower member of the inserting device.

Fig. 10 is a cross section on line 10—10 of 75 Fig. 9, after the upper member has been lowered ready for insertion in the package.

Referring to Fig. 3, the time sheet 20 is arranged for conveniently keeping a record of the time of a number of workmen on a certain job for a certain period of time, such as two weeks. Each line across the sheet shows a workman's number, name, itemized record of days he worked, with the total thereof, his rate of pay, the amount earned, the amount advanced prior to the regular pay day, the balance due on pay day, and a space for remarks.

When pay day arrives the time sheet 20 is cut into strips 22 as shown in Fig. 4, each 80 strip bearing the account of the workman whose name it bears. The strip 22 in Fig. 4 shows that workman number 24 worked 11 days at the rate of \$2.40 per day, that he had drawn no advance money and was therefore entitled to draw \$26.40 on pay day.

Figs. 1, 2 and 5 illustrate how this amount and the statement of account are arranged in the pay envelope. There are two ten-dollar bills, one five-dollar bill, one one-dollar bill, a 85 100

silver twenty-five cent piece, a silver ten-cent piece, and a five-cent piece, all of which taken together total \$26.40.

The envelope is designated 26. It is preferably wholly transparent, but in any event it is provided with sufficient transparent surface to allow all its contents to be read and counted.

The bills 28 are arranged in overlapping relationship so that their respective denominations are all visible. The metal coins are, for convenience, held in position by a perforated card 30 such as is commonly used for sending coins by mail.

The statement of account 22 is placed in position folded around one end of the money, and a wire clip or other releasable device 32 is applied to hold the money and statement in their prearranged relative positions, after which they are inserted in the envelope and the package sealed, the final appearance of the package being evident from Fig. 1, in which it will be seen that the workman's name, number, and the statement of his account (the folded portion being readable from the rear of the package) may be read, and the money may all be counted, without opening the package.

The envelope bears an inscription reading, "Do not open envelope before counting the money contained therein. No complaints will be considered after opening the envelope."

It has been found in actual service that the above described system has practically abolished payroll disputes wherever it has been adopted.

A convenient device for assembling the money and statement and for depositing them in the package is shown in Figs. 7, 8, 9 and 10.

This device comprises a plate member 34 and a substantially similar member 36, hinged together at 38. The plates 34 and 36 are of such size that when folded together they easily slip into the envelope as in Fig. 7.

Plate 34 is provided at one edge with a guide member 40. I prefer to make 40 of cloth or similar fabric, stiff enough to serve as a guide, and to normally hold itself in the position shown dotted in Fig. 10, but easily pressed to the full line position when member 36 is in closed position.

The opposite edge of plate 34 has a similar but smaller guide 42 for assisting the operator to place and hold the strip 22 in position.

With the above description in mind it will be readily understood how the material is assembled preparatory to inserting it in the package. Member 36 being raised, one end of strip 22 is placed in guide 42. The other end of the strip will project well beyond the end of plate 34. Then the bills 28 are arranged in guide 40 on plate 34 and on top of guide 42. Then card 32 is placed on top of

bills 28 in guide 40, the free end of strip 22 is folded over, and the upper member 36 is lowered, thus enclosing the money and statement between plate members 34 and 36. It will be appreciated that when the device is then grasped by the operator its contents will be securely held in their prearranged position; and will permit the attachment of clip 32 to bills 28, strip 22, and card 30 as is best seen in Figs. 2, 5 and 6. For the convenience of the operator in applying clip 32, the plates 34 and 36 are recessed and partly cut away as at 44 and 46. The device and its contents are then inserted in envelope 26 to the position indicated in Fig. 7.

Plates 34 and 36 are provided at their free ends with open end slots 48 and 50. To remove the inserting device from the envelope the operator grasps the envelope tightly with finger and thumb in the space provided by slots 48 and 50 and then withdraws the inserting device by grasping its hinged end. During the withdrawing operation bills 28 and card 30 are in the grasp of the operator, and the statement 22 is secured to the money by clip 32 and by reason of being folded over the end of the money. Therefore, when the inserting device is withdrawn plates 34 and 36 and guides 40 and 42 slip off the contents, leaving the money and statement in their prearranged positions, where they are held by clip 32 after the package has been sealed.

It is to be understood that the invention is not limited to the construction herein specifically illustrated but can be embodied in other forms without departure from its spirit as expressed by the claims.

I claim—

1. A sealed money envelope having transparent portions and containing money bills in overlapping arrangement with the value indications of each and all of the bills displayed through the transparent portions of the envelope to permit visual determination of the total amount of paper money within the envelope to be made while the envelope remains sealed, said envelope containing also a coin card having coin-receiving pockets exposed to the transparent portions of said envelope to permit visual determination of the total value of all of the coins contained in the coin card in the package to be made while the envelope remains sealed.

2. An envelope as set forth in claim 1 and containing a statement of the account being paid by the contained money, the said statement of account being readable through transparent portions of the envelope while the latter remains sealed.

3. A sealed money envelope having transparent portions and containing a plurality of pieces of money so arranged in the envelope that the full value may be determined through the envelope without opening the latter, and means within the envelope bearing

information including the name of the payee, the statement of the amount due him, and the name of the payor, such information being readable through the envelope before the latter is opened.

4. A sealed money envelope having transparent portions and containing money bills in overlapping arrangement with the value indications of each and all of the bills displayed through the transparent portions of the envelope to permit visual determination of the total amount of paper money within the envelope to be made while the package remains sealed, and containing a statement of the account being paid by the contained money, the said statement of account being readable through transparent portions of the envelope while the latter remains sealed.

5. A sealed money envelope having transparent portions and containing a coin card having coin-receiving pockets exposed to transparent portions of said envelope to permit visual determination of the total value of all of the coins contained in the coin card in the envelope to be made while the envelope remains sealed, and containing a statement of the account being paid by the contained money, the said statement of account being readable through transparent portions of the envelope while the latter remains sealed.

In testimony whereof I hereto affix my signature.

DANIEL E. DE MARQUEZ.
